UNITED STATES PATENT OFFICE.

ANTONANGELO NEGROMANTI, OF MILAN, ITALY.

DEVICE FOR HEATING BY ELECTRICITY.

1,374,091.

Specification of Letters Patent. Patented Apr. 5, 1921.

Application filed October 4, 1920. Serial No. 414,647.

To all whom it may concern:

Be it known that I, ANTONANGELO NEGROMANTI, subject of the King of Italy, and resident of Milan, Italy, have invented certain new and useful Improvements in and Relating to Devices for Heating by Electricity, of which the following is a specification.

The present invention relates to a device for heating by electricity.

The object of the invention is to provide an arrangement of parts whereby the heat produced by electricity is previously stored in a mass of accumulating material and communicated to a piping wherein a fluid is circulated and conveyed to the apparatus to be heated.

A driving apparatus is generally inserted into said pipe in order to impart to said fluid the necessary velocity required by the rate of subtraction of the heat.

In the annexed drawing is represented by way of example a form of construction of the invention applied to a cooking stove.

Figure 1 is an elevational view partly in section of the device combined with the stove.

Fig. 2 is a plan view partly in section of same.

Fig. 3 represents a sectional view of the electrical heater.

Fig. 4 is a plan view of said heater the cover of which is removed.

The combined construction comprises the base —1— the walls —2— and the cover —3—.

A chamber —1— is formed within said structure, said chamber being closed within walls —4— and ceiling —5—. Said chamber is filled up with heat-storing material as silicon-sand and the like.

Within said storing material, electrical heaters —6— are embedded said heater being constituted in any known form and preferably comprising carbon powder —7— inclosed in flat boxes —8— made of iron enameled in the interior to isolate said powder.

Copper bars —9— fitted in intimate contact with said powder and emerging from said boxes into the form of laminated con-

tacts —10— are suitably isolated from the metallic walls and constitute the terminals of the heaters.

Said heaters through their terminals are electrically connected to the conductive bars —11— which are in electrical connection with the electric wires —12—.

Within the heat-storing material is embedded a spirally shaped pipe —13— one end of which issues from the stove at —14— and is connected to the outlet of a centrifugal pump —15— the other end being connected to a collecting pipe —16— mounted above the ceiling —5— of the heating chamber.

From said collecting pipe depart pipes or columns —17— the upper ends of which are connected to receptacles —18— the covers of which are made of corrugated metal.

Said receptacles or secondary heaters are lodged in suitable recesses of the cover —3—.

From another point of the wall of each receptacle or rather from the bottom of same depart the pipes —20— which communicate with the collector —21— and from said collector a pipe —22— returns to the pump.

The liquid driven by said pump is preferably of a kind having a high boiling point as oil, vaseline, glycerin, paraffin and the like.

The pump is driven by an electric motor —27—.

On the ceiling —5— and between the latter and cover —3— an oven —23— is formed vertically crossed by the columns —22— and surrounded by the collecting pipe —16—.

—24— is a door. Between the walls —4— and the walls of the stove a water jacket may be formed which should catch the heat tending to be wasted. —25— is a cock for the flow of the heated water.

—26— are valves actionable from outside to regulate the flow of the liquid and the conveyance of heat to the secondary heaters.

Having now particularly described the nature of my invention and the manner in

which the same should be performed I claim:

A device for heating by electricity comprising electrical heaters, a mass of heat accumulating material to store the heat produced by said heaters, a circulating pipe containing a liquid with high boiling point, said pipe having a spiral section embedded in said accumulating material, a pump in-

serted in said circulating pipe, branches in 10 said circulating pipe to convey the liquid to receptacle for which the heat is intended, and valves to regulate the flow of heated liquid from and to said receptacles.

Signed at Milan, in the county of Lombardy and State of Italy, this 2 day of September, A. D. 1920.

Sig. ANTONANGELO NEGROMANTI.
